UNITED STATES PATENT OFFICE

171,164

LIGHTING FIXTURE OR SIMILAR ARTICLE

Jack Morgan, Chicago, Ill., assignor to Industrial Lamp Corporation, Elkhart, Ind., a corporation of Illinois

Application April 23, 1953, Serial No. 24,637

Term of patent 14 years

(Cl. D48—4)

To all whom it may concern:

Be it known that I, Jack Morgan, a citizen of the United States, residing at Chicago, in the county of Cook and State of Illinois, have invented a new, original, and ornamental Design for a Lighting Fixture or Similar Article, of which the following is a specification, reference being had to the accompanying drawing, constituting a part hereof.

Figure 1 is a perspective view of a lighting fixture, showing my new design;

Figure 2 is a side elevational view thereof showing the side opposite that shown in Figure 1; and

Figure 3 is an end elevational view looking at the left of Figure 2, the dotted lines indicating a bracket being omitted for convenience of illustration.

The dominant features of my new design for a lighting fixture are shown in solid lines.

I claim:

The ornamental design for a lighting fixture or similar article, substantially as shown and described.

JACK MORGAN.
